STOCKING

Louis H. Mendelsohn, Paterson, N. J.

Application July 2, 1936, Serial No. 88,604

1 Claim. (Cl. 66—187)

In the foot of an ordinary stocking or sock no account is taken of varying conformations of the human foot except as to length. In fact, the garment foot is not made ideally to conform to even a standard human foot of the same length, but rather it at best merely approaches its form as nearly as possible and the garment "fits" only because it has some ability to stretch and of course the incidental stretch is not uniform throughout the whole extent of the garment foot. When, therefore, varying shapes of human feet have to be taken into account the ordinary stocking or sock is very likely to cause discomfort, especially in walking, usually by creasing or rolling or bunching as an incident of overstretching in some parts with little if any stretching and hence slackness in others; this is of course aggravated if the garment is somewhat oversize in point of length. Usually, since the variations in form of the human foot are quite pronounced at the toe portion, from extreme tapering to extreme stubbiness, this condition is most likely to be experienced at the toe portion of the garment. Not only is there discomfort incident to the creasing or deformation of the toe portion but such toe portion presents an unsightly appearance if the garment is worn with a sandal or other outside foot-wear which appreciably exposes the toe portion.

The invention relates to full-fashioned hosiery and it consists in certain improvements in hosiery of this particular class whereby the indicated faults are overcome. That is, according to the invention the toe-portion or toe-zone (usually accepted and here taken to include all that portion of the garment foot which extends from the toe tip back to a transverse line at least half-way between such tip and a transverse plane that will coincide with the wearer's metatarsal arch) of a full-fashioned foot garment has that segment thereof which is approximately coincident in width with such zone and which extends across and over and around the wearer's toes and terminates at both its ends approximately at the longitudinal seamline knitted reticular and being also substantially uniformly elastic and yielding throughout its whole extent and having all of its yarn elements which define the holes in said segment more resistant to wear throughout said whole extent than those of the adjoining herein defined major portion of the garment; that is to say, said segment is without any knit formation that is not reticular but plain-knitted, such as so-called "diamond-points" (or insets or gussets), or seaming or other structure that would cause the garment to manifest a disparate resistance to

stretching influence and so be likely to undergo bunching or rolling actually within said segment. In any previous foot garment having in its toe zone a region knitted reticular such formations, as for instance the mentioned diamond points, have invariably existed within the indicated segment of the garment, with the mentioned faults as incidents of their use. I am also aware that it has been proposed to provide the foot of a knitted foot garment with a narrow reticular band to surround the wearer's foot in coincidence more or less with the metatarsal arch, but such construction, while it may perhaps subserve its intended purpose of suiting the one garment to varying foot-lengths, obviously contributes nothing to the particular purpose that my invention is intended to accomplish.

In the drawing,

Figs. 1 and 2 are, respectively, top and bottom fragmentary plans of the improved garment foot; and

Fig. 3 is a plan of the blank from which the garment foot as shown in Figs. 1 and 2 is formed.

Referring to Figs. 1 and 2: The toe-zone as to width here extends from the tip of the toe to a transverse plane approximately halfway between such tip and a transverse plane which will coincide with the wearer's metatarsal arch when the garment is worn. The mentioned reticular segment of this zone is designated 1 and is nearly as wide as such zone and it is formed to extend across the wearer's toes as shown in Fig. 1 and to terminate at its ends under them, as shown in Fig. 2, such ends being here formed by straight lines parallel to each other in the finished or seamed foot and near and also parallel to margins of the foot as it exists in the blank (Fig. 3), thus leaving narrow plain-knitted selvages at 4 in this example.

As the blank is shown in Fig. 3 its margins extend parallel at 6, then converge at 8 and then extend parallel again at 10 to form the knit margins of a plain-knitted region which, when the blank is seamed at 6 and folding of said region is effected on lines 11 and seaming is also done at 7, leaves the foot with a plain-knitted toe-tip 8.

In the present example the region 2, back of the toe-zone, as well as the regions 4 and 5, is knitted plain excepting that in region 2 and paralleling and relatively back of the toe zone there may be a line of ornamental picot stitches 3.

Having thus fully described my invention what I claim is:

The herein described full-fashioned foot gar-

ment having all that segment thereof which is approximately coincident in width with the herein defined toe-zone of the garment and which, when the garment is worn, extends across and over and around the wearer's toes and terminates at both its ends approximately at the longitudinal seam-line knitted reticular and being also sub-

stantially uniformly elastic and yielding throughout its whole extent and having all of its yarn elements which define the holes in said segment more resistant to wear throughout said whole extent than those of the adjoining herein defined 5 major portion of the garment.

LOUIS H. MENDELSOHN.
